United States Patent Office.

JOSHUA B. GRAVES, OF NEW YORK, N. Y.

Design No. 4,618, dated January 31, 1871.

DESIGN FOR A CASTER-BOTTLE.

The Schedule referred to in these Letters Patent and making part of the same.

To all whom it may concern:

Be it known that I, JOSHUA B. GRAVES, of the city, county, and State of New York, have invented a new and original Design for Caster-Bottles; and I do hereby declare that the following is a full, clear, and exact description thereof, which will enable others skilled in the art to make and use the same, reference being had to the accompanying drawing forming part of this specification.

This invention relates to a new and original design for bottles for casters for table use, and consists in the form and design of the body of the caster, by means of which a bottle with square sides is made to fit any caster.

In the accompanying drawing—

Figure 1 represents an outside view of my improved caster-bottle.

Figure 2 is a cross-section of fig. 1, on the line $x x$.

Figure 3 is a cross-section of fig. 1, on the line $y y$
Figure 4 is a cross-section on the line $z z$ of fig. 1
Similar letters of reference indicate corresponding parts.

A is a portion of the bottle having four sides, with the angles ornamented in any manner to suit the taste.

B is a circular portion, which fits into the orifice in caster, by means of which the bottle is made to fit any caster while it has square sides, as seen in fig. 4.

The lower portion C is an octagon in shape, as shown.

I claim as my invention—

The design for a caster-bottle, as shown.

JOSHUA B. GRAVES.
